(57) **CLAIM**

The ornamental design for a cutting board, as shown and described.

DESCRIPTION

FIG. 1 is a first perspective view of a cutting board, showing my new design;

FIG. 2 is a bottom perspective view of the cutting board of FIG. 1;

FIG. 3 is a top plan view of the cutting board of FIG. 1; FIG. 4 is a bottom plan view of the cutting board of FIG. 1; FIG. 5 is a right elevational view of the cutting board of FIG. 1;

FIG. 6 is a left elevational view of the cutting board of FIG. 1;

FIG. 7 is front elevational view of the cutting board of FIG. 1;

FIG. 8 is back elevational view of the cutting board of FIG. 1; and,

FIG. 9 is a second top perspective view of the cutting board of FIG. 1, shown in environmental use.

The broken lines in the drawings are for showing portions of the cutting board and form no part of the claimed design. The broken lines flexible sheets shown inside the cutting board in FIG. 9 are included to show environment and form no part of the claimed design.

The dot-dash broken lines in the drawings immediately adjacent to the claimed areas represent the boundaries of the design and form no part thereof.

None of the broken lines form any part of the claimed design.
